ATTORNEY

UNITED STATES PATENT OFFICE.

EDWARD J. DAILEY, JR., OF NEW YORK, N. Y., ASSIGNOR TO HOLOPHANE GLASS CO.
INC., A CORPORATION OF NEW JERSEY.

SHADE-HOLDER.

1,387,474.

Specification of Letters Patent. Patented Aug. 16, 1921.

Application filed December 18, 1919. Serial No. 345,723.

To all whom it may concern:

Be it known that I, EDWARD J. DAILEY, Jr., a citizen of the United States, and resident of New York city, in the county of New York and State of New York, have invented certain new and useful Improvement in Shade-Holders, of which the following is a specification.

The object of my invention is the manufacture of a shade holder, which is adapted to hold the shade in normal position and at the same time is capable of adjustment to angular position with ease and permanency.

Figure 1 is a vertical elevation of a shade holder partially in section, embodying my invention and

Fig. 2 is a blank showing the method of stamping out an essential part of the device.

In the figure 1 is the lamp socket, 12 is the lamp, and 2 is the holder encircling the lamp and socket. The holder consists of depending arms 4, attached to a ring 3, which grips the socket or is attached to it in the usual way. These arms are generally four in number and have apertures 5, extending along their lengths. A sleeve member 6 is attached to the arms by means of pins 7 which fit into the apertures and it is by means of these pins and apertures that the various adjustments are maintained. The shade or reflector 11 is supported by the suspension of its upper portion or neck on the sleeve 6 and a movement of the sleeve 6 will cause a similar movement of the shade. On the outside of the neck of the shade is placed a ring 9 having a screw top 10, the lower part resting on the outer neck of the shade and the screw top 10 screwing on to the screw threaded top 8 of the inner sleeve 6. Parts 9 and 10 are not absolutely necessary but are used to prevent any accidental displacement of the shade during adjustment.

The methods of attachment and adjustment are as follows: The sleeve 6 is slipped under the shade so that the screw threaded collar 8 and the pegs 7 protrude therefrom. The arms 4 of the holder, which are made of resilient metal which can be compressed and forced into the neck of the shade, are pushed down the sleeve and neck until the desired apertures in the arms are reached. The pins are then slipped into the upper part of the apertures in the arms at this

point and the weight of the shade pulls them down to the lower contracted part of the apertures. Where an angular adjustment is required two of the apertures are used as pivots and the shade rocked upon them and the pin of the portion of the sleeve carrying the shade intended to be depressed is placed in a relatively lower aperture, while the pin of that portion intended to be raised is placed in a relatively higher aperture. These apertures are spaced and calculated on the arms for different types of lamps, shades and adjustments, which features may be indicated directly on the holder or by means of directions accompanying them. The ring 9, 10 is then permitted to slide down on the arms and its screw thread revolved about the screw thread 8 of the inner sleeve 6. This serves as an additional support. It will be observed that the shade holder can be used as a conventional shade holder in normal position, and can also be used in a great variety of angular positions. While I prefer to use four arms in angular positions, any number can be used. The holder can be made of any material as long as there is a certain resiliency in the arms. It can be used in shades and reflectors having collars as well as collarless shades, and the positions of the various sleeves are immaterial, as what is desired in the device is the wide range of adjustability of the holder parts obtained by manipulation of the pin members or their equivalents into apertures in the depending arms of the holder.

I claim:

1. A shade holder comprising: a socket retaining member having a plurality of dependent arms, a shade retaining member fitting over the arms and provided with means of retention by the dependent arms to permit of angular adjustment of the shade.

2. A shade holder comprising: a socket retaining member having a plurality of dependent arms, a sleeve member fitting over the arms and adapted to retain the neck of the shade, the sleeve being provided with means of retention by the dependent arms to permit of angular adjustment of the shade.

3. A shade holder comprising: a socket retaining member having a plurality of dependent arms, a ring member fitting over

the neck of the shade, a sleeve member fitting over the arms and under the ring and shade and provided with means of retention by the dependent arms.

5. A shade holder comprising: a socket retaining member having a plurality of depending arms, a sleeve member fitting over the arms and adapted to retain the shade, and provided with retaining pins adapted to fit in apertures in the retaining arms to permit of angular adjustment of the shade.

10. 6. A shade holder comprising: a ring fastened around the socket, a plurality of arms pendant from the ring having a series of apertures therein, a sleeve member fitting

over the arms and adapted to retain the shade, the sleeves being provided with pins adapted to fit in the apertures to permit of angular adjustment of the shade.

7. A shade holder comprising: a socket 20 retaining member, a plurality of arms pendant from such member having a series of apertures therein, and shade holding means provided with pins adapted to fit in the apertures to permit of angular adjustments 25 of the shade.

Signed at New York city in the county of New York and State of New York, this 16th day of December, A. D. 1919.

EDWARD J. DAILEY, JR.
